UNITED STATES PATENT OFFICE

2,456,804

THREAD FINISHING MACHINE

Albert E. Winslow, Norwich, Conn., assignor, by
mesne assignments, to Universal Winding Com-
pany, Cranston, R. I., a corporation of Massa-
chusetts

Original application January 11, 1944, Serial No.
517,862. Divided and this application Decem-
ber 9, 1944, Serial No. 587,388

5 Claims. (Cl. 34—154)

1

This application is a division of my co-pending application Serial No. 517,862, filed January 11, 1944, now Patent Number 2,400,325.

This invention relates to a thread finishing apparatus for the application of a coating or size which may be desirable for various purposes.

Threads of different materials require different finishing in order that the threads may be manipulated in such machines as knitting, braiding, weaving, or the like, where the threads are subjected to friction in the working of the threads into various fabricated articles. In the application of the coating or sizing heat is required for drying the sizing on the thread. The heat which is required for drying the thread in a machine which is in use today lacks control and the room in which such a machine is operated becomes excessively warm and uncomfortable especially in hot weather while at the same time there is an undesirable loss of heat. In machines which are used today the assembling package upon which the sized thread is packaged usually supplies the pull on the thread to draw it through the machine in which the sizing is applied. Such an arrangement makes it difficult to control the speed of the ever growing package that an even feed may be had and much slip and lost motion with consequent wear on the friction driving belt is experienced. Further the slip makes stretching of the thread difficult.

One of the objects of this invention is to provide an apparatus in which the heating chamber will be nicely controlled to conserve the heat and apply it to the threads without excessively heating the room.

Another object of the invention is to improve the drying of the coating applied to the threads.

Another object of the invention is to provide an arrangement so that the heating chamber will have heating energy applied thereto only during the time that the machine is operating. The heating chamber being automatically turned off when the machine is stopped.

Another object of the invention is to provide adjustment of the means of distributing the size over the thread that the desired coating may be had.

Another object of the invention is to control the thread action by control of the temperatures which it is successively subjected to.

With these and other objects in view, the invention consists of certain novel features of construction, as will be more fully described and particularly pointed out in the appended claims.

In the accompanying drawings:

2

Fig. 1 is a diagrammatic view illustrating the apparatus from the supply packages through the coating machine and to the take-up creel;

Fig. 2 is a central sectional view through the coating machine;

Fig. 3 is an elevation partly in section illustrating the drive for the various rotating parts of the machine with drive to shaft 60 omitted;

Fig. 4 is a diagrammatic view illustrating the 10 means of driving or supplying power to the main drive shaft of the machine;

Fig. 5 is a sectional view showing the mounting of the heating chamber;

Fig. 6 is a top plan view of the machine with 15 the heating chamber omitted and illustrating the arrangement of the driving belt for the various rotating parts;

Fig. 7 is a plan view on a somewhat larger scale showing the entering end of the machine;

Fig. 8 is a plan view partly in section illustrating in somewhat more detail and on a larger scale the delivery end of the machine;

Fig. 9 is a sectional view taken on line 9—9 of 20 Fig. 8 illustrating the mounting of the delivery roll at the entering end of the machine illustrated in Fig. 8;

Fig. 10 is a section of the same parts taken on line 10—10 of Fig. 8;

Fig. 11 is a sectional detail illustrating the 25 drive for the traverse bar;

Fig. 12 is a lateral section through the brush chamber of the machine;

Fig. 13 is an elevation illustrating a brush adjusting mechanism;

Fig. 14 is an elevation of a pair of supply packages;

Fig. 15 is a sectional view of the cooling unit; and

Fig. 16 is a diagrammatic view of the electrical 30 circuit of the apparatus.

In proceeding with this invention the general plan is to draw threads by feed rolls from a plurality of supply packages, which threads will be gripped and arranged in side-by-side relation for the width of the machine making in effect a web of threads for feeding through the machine. The threads are also gripped by a pair of delivery rolls which travel at a surface speed greater than the surface speed of the feed rolls. This results 35 in a stretching of the threads between these two feed rolls. A coating or sizing is applied to the threads at this entrance and this sizing is dried upon the threads as they advance through the machine. Drying is done by applying controlled

heat to the web of threads and by also brushing 40 45 50 55

the threads. The brushing serves to spread the coating or sizing on the threads and also serves by its friction on the threads to assist in the drying of them. Brushing takes place at several different points between the feeding in and delivery nip rolls and affects a polishing of the coating which is applied to the threads. As soon as the threads emerge from this coating machine they are chilled at a point below room temperature which serves in many cases to limit the contraction of the thread which might occur after having been stretched. However, in order to positively prevent any contraction, each thread is maintained under a substantial tension, and packaged on a non-collapsible spool as it emerges from the machine.

The apparatus may be considered as being in three parts and in Fig. 1 of the drawing I designate A as a supply creel, B the coating unit or machine, and C the take-up or packaging creel. The yarns are maintained under tension from the time they leave the supply creel until they are wound on the packages at C.

The supply creel consists of a plurality of pins 15, 15' arranged in pairs upon which headless packages 17, 17' may be mounted. Each strand is drawn from one of these packages while the opposite end 18 of the strand from this package is tied onto the lead-off end 19 of the strand on the companion package mounted on an adjacent pin. Thus, as one package runs out the next package starts to furnish the supply. The operator replaces the run-out package with a fresh one tying the lead-off end in the fresh package to the tail end of the package which is operating. Thus, no stopping of this machine need occur for furnishing a supply of the thread which is to be sized. This method of furnishing a supply is known in the textile industry.

The operation on the thread at the machine or unit B involves some novel steps as well as new apparatus and will be explained and claimed in detail in this application. The unit C provides a take-up for each strand or yarn end and while any take-up mechanism may be utilized so far as this machine is concerned which will maintain a tension on the yarn I have illustrated herein a novel form of take-up mechanism which will be described and claimed in greater detail in my co-pending application Serial No. 517,861, now Patent No. 2,400,324.

With reference to the machine, designated B, as a part of the apparatus, I have provided a suitable framework 20 in which various parts are mounted in bearings for rotation and as shown in Fig. 6 there are mounted at spaced intervals along the framework 20 shafts 21, 21', and 21'', each mounted at each end in an adjustable bearing 22 (see also Figs. 12 and 13) which is carried by the slide 23 in turn vertically adjustable in guideways 24 which are fixed on the framework of the machine. The amount of adjustment is indicated by the scale 25 and datum line 26 and is effected by the threaded shaft 27 which extends through the worm gear 28 having a threaded bore to engage therewith. The worm gear meshes with the work 29 (see Fig. 12) which may be actuated through the shaft 30 by the crank 31. A duplicate arrangement of shaft 27', worm gear 28', worm 29', provides for the adjustment of the opposite ends of each of the shafts 21, 21', 21'' heretofore mentioned. Upon each of the shafts 21, 21', or 21'', a brush 32, 32', 32'' is mounted for rotation as the shaft is driven.

At the feeding in end of the machine a pair of

nip rolls 35 and 36 (see Fig. 2) are provided to grip the thread between them and prevent a slipping of the threads with reference to either of these rolls, while a similar pair of rolls 37 and 38 are provided at the delivery end of the machine so as to draw the threads from the feed-in rolls 35 and 36 across the brushes 32, 32', and 32''. The delivery rolls are driven at a surface speed sufficiently greater than the feed-in rolls to stretch the threads as they pass through the machine.

The upper rolls 35 and 37 of each of the pair of nip rolls are fixed while the lower rolls 36 and 38 of each pair are eccentrically mounted with reference to the center of these upper rolls 35 and 37. This mounting is illustrated in greater detail for the set of rolls 37, 38 in Figs. 8 to 10, while the mounting of roll 36 is similar thereto. The center shaft of the upper roll 37 is designated 40 and at either end a boss or eccentric portion 41 is mounted on this shaft. This boss 41 forms a bearing for the encircling annulus 42 which is mounted upon it and which forms a part of the bracket 43. This bracket carries shaft 44 upon which the lower roll 38 is mounted. As this bracket 43 rotates about its bearings 41 the roll 38 will move toward or from the upper roll 37 indicated in dot dash lines in Figs. 9 and 10. These brackets at both ends of the roll are moved in unison by means of the segmental gears 45 formed on the brackets which mesh with pinions 46, the pinions 46 being fixed on a shaft 47 extending from one side of the machine to the other. The shaft 47 is provided with a worm gear 48 (see Fig. 8) at one end which meshes with a worm 49 operated by shaft 50 through the means of a crank which engages the slot 51 in the enlarged head thereof. While the weight of this larger roll of the two feed or delivery rolls is such that each would swing about its eccentric mounting by means of gravity so as to firmly grip the threads, the worm gear means provide a positive arrangement by which these rolls may be brought into firm nipping engagement with the threads to provide a good bite thereon.

At the feed-in end of the machine the lower nip roll 36 is similarly mounted and swings into a trough 50 which contains a sizing bath 51 and thus serves to immerse the threads 52 as they lead into the machine beneath the roll 36, thence up over the roll 35 and toward the delivery rolls 37 and 38.

It is desirable that all of the rotating parts be operated in unison. The drive of the machine 55 comprises a main drive shaft 60 (see Fig. 6) which is driven by a low speed motor 61 (see Fig. 4) through belt 62 onto the large pulley 63 which is connected to the drive shaft 60 through an overrunning clutch 64. There is also provided upon the shaft 60 a high speed drive which consists of a motor 65 which operates through a Reeves drive 66 from which there extends a belt 67 to a pulley 68 which is fixed upon the shaft 60. When this belt drives the shaft at high speed, the shaft 60 will operate freely without being retarded by the pulley 68 by reason of its connection to the shaft through the overrunning clutch 64. At the inner end of the shaft 60 a gear 69 is provided. This gear 69 drives the gear 70 on the upper shaft 40 of the delivery rolls 37. Upon this shaft 40 is provided another gear 71 which meshes with the gear 72 on the shaft 44 upon which is mounted the larger roll of the delivery pair 38.

The inner end of this shaft 60 (see Figs. 3 and 6) is also provided with a pulley 74 over which

runs a belt 75 to drive a pulley 76 on shaft 77 at the opposite end of the machine upon which shaft 77 there is a gear 78 which meshes with a gear 79 on the shaft 80 (see also Fig. 7) for driving the upper feed-in roll 35. This belt 75 extends beneath idlers 81 and 82 which are mounted on brackets 83 and 84 (see Fig. 3) and adjusted about the supports 85 and 86 so as to exert the desired amount of tension on the belt 75 of the drive of these nip rolls for feeding and delivering the work. The arrangement is such as to sizes or diameters of the rolls that the delivery rolls will be driven faster than the feed rolls so as to exert from one to twenty per cent stretch in the threads which pass through the machine.

On the shaft 80 there is a gear 87 which drives gear 88 on shaft 89 upon which the lower feed roll 36 is mounted and by means of which it is driven.

In order to effect a drive with the brushes pulley 90 is provided on shaft 60 (see Figs. 3 and 6) which drives pulley 91 on shaft 21" by belt 92. A second pulley 93 on this shaft 21" furnishes drive through belt 94 to pulley 95 on shaft 21' which may be tensioned by idler 96 on bracket arm 97 (see Fig. 3) by adjustment around shaft 98. Pulley 99 on shaft 21' serves as a means for driving belt 100 which engages pulley 101 on shaft 21 to drive the same, this belt 100 being tensioned by means of pulley 102 (see Fig. 3) adjustably by bracket arm 103 around the shaft 104.

Traverse bars at both ends of the machine are provided for traversing the threads across the roll. At the delivery end of the machine, a spiral gear 110 (see Fig. 11) is mounted on the shaft 40 and engages spiral gear 111 to operate shaft 112 upon which the crank 113 is mounted so that its pin 114 will extend into the slot of a guide 115 so as to oscillate the bar 116 which carries pins 117 back and forth to move the threads 52 which extend between the pins back and forth across the roll. The feed-in end of the machine is provided with a similar traverse, there being there illustrated the spiral gear 111', the shaft 112', and crank 113'. In this case, however, instead of engaging the traverse bar 120 directly a pitman 121 is provided for engaging the crank pin 114' which is pivoted as at 122 on the arm of a bracket 123 which bracket extends to the traverse bar 120 for oscillating the same.

The traverse bars 116 and 120 are mounted upon pins 125 at either end suitably supported by brackets 126. Pins 117 are provided on each of these bars for leading the threads therethrough.

While the brushes serve to spread and dry to some extent the coating which is applied to the thread a heating chamber is desirable and in this connection I have provided a heating arrangement designated generally 130 (see Figs. 2 and 5). This heating arrangement consists of a dish-like inverted casing 131 having a closed top with side and end flanges 132. A framework 133 serves to mount this casing in position over the top of the brushes and is provided with a bar 134 which will engage the web-like form of threads extending through the machine and serve to press them downwardly so that they will engage the brushes 32, 32', 32". One of these bars is positioned between adjacent brushes. Within this casing 131 I provide some suitable heating means which I have here shown as

lamps 135 (see Fig. 2), known as infra red lamps, which afford a penetrating heat to the coating and effect a quick drying of the coating on the threads. Reflectors 136 may be provided to assist in projecting the heat from these lamps for the drying of the coating on the threads. This entire casing 130 may be lifted by means of a handle 137 which extends along the casing lengthwise thereof and affords an easy means to lift the casing if it is desired to enter the interior of this coating machine for threading the same up. A suitable counterweight may be provided for the lifting of the casing.

In order to confine the heated air which may be picked up by the brushes I have encased each of the brushes in a sheet metal casing designated 140, 140', and 140" and provided an exhaust 141, 141', 141" from the several chambers, so that the brushes may drive the heated air downwardly pulling it into and through the spaces 20 between the web of threads which is formed. In order to assist exhausting of the pipe, I have provided a fan 142 which will suck out the common pipe 143 to which each of these chambers 25 140, 140', and 140" is connected to provide greater efficiency in drying the threads.

Where synthetic fibers are operated upon it may be desirable to chill these fibers immediately that they have emerged from the heating and stretching operations preventing them from recovering or returning to their state prior to stretching. This chilling may be provided by means of a set of pipes 145 (see Fig. 15) which are colder than room temperature and which are housed in a compartment 146 having a hinged cover 147 and through which the web of threads are led. A suitable seal 148 is provided for passage of the threads into and from the compartment 146.

The arrangement is such that for threading up a broken end an operator will use an electrical control to throw the slow speed motor into operation and pull a thread from the supply creel and drop it onto the web of threads which is entering the machine. The thread will feed through onto the top of the lower feed roll where it may be picked up by the operator and then carried manually up over the top roll and over the brushes, the operator lifting the heating unit 40 to some extent in order to provide access, the amount of lifting depending upon how deep into the machine from the front it is desired to reach. The operator then will drop the end of the thread onto the web of traveling threads at 45 the delivery rolls and this thread will travel around the rolls and emerge on this web where it may be easily picked up by the operator and carried to the take-up creel and there caused to wind onto the take-up bobbin from which it was severed. After which the operator may push the button in order to start the machine up again at high speed to continue the sizing operation at a rapid rate.

In Fig. 16 I have illustrated a wiring diagram from the line to the two motors 61, 65 and including the heating means 135. The switch 150 may be manipulated to cause operation of either the slow motor 61 or the fast motor 65 while the switch 151 for stopping and starting the motors 70 is arranged ahead of the heating means 135 so that when energy is turned off to the motors the heating means is also turned off so that the threads when not moving cannot be subjected to 75 excessive heat.

I claim:

1. In a thread finishing apparatus, a heating unit through which sized threads pass comprising brushes positioned to engage the threads to distribute the size thereon, a heating chamber for drying said size on the threads positioned directly over said brushes and comprising top, side and end walls with an open bottom over the threads, means for feeding the threads through the chamber, means in the chamber to generate heat, a casing about said brushes opened at one end adjacent the path of the threads and having an opening in a wall opposite the opened end, said brushes drawing the heat downwardly through the threads and out through said opening to dry the threads.

2. In a thread finishing apparatus, thread guides at each end portion of the apparatus for guiding the threads in spaced relation through the apparatus, a drying unit comprising a chamber, means for feeding the threads through the chamber, a series of rotary brushes contacting the threads as they pass through the chamber to distribute the size thereon, a casing about said brushes opened adjacent the path of the threads and having an opening in a wall thereof through which air may discharge, and heating means positioned directly above the brushes and cooperating therewith to dry the treated threads, said brushes drawing the heat through the threads and out of said opening.

3. In a thread finishing apparatus, a drying unit comprising a chamber, means for feeding the threads through the chamber, a series of rotary brushes contacting the threads as they pass through the chamber, a casing about each of said brushes of generally trough shape opened adjacent the path of the threads and having an opening in the bottom, and heating means on the other side of the thread from said brushes and open bottom cooperating with the brushes to dry the treated threads, said brushes drawing the heat through the threads and out through said opening.

4. In a thread finishing apparatus, a drying unit comprising a chamber, means for feeding the threads through the chamber, a series of rotary

brushes contacting the threads as they pass through the chamber, a casing about each of said brushes of generally trough shape opened adjacent the path of the threads and having an opening in the bottom, and heating means on the other side of the thread from said brushes and open bottom cooperating with the brushes to dry the treated threads, said brushes drawing the heat through the threads and out through said opening, and exhausting means operatively connected to said casings to draw the heat from the heating means across the thread.

5. In a thread finishing apparatus, a drying unit comprising a chamber, means for feeding the threads through the chamber, a series of rotary brushes contacting the threads as they pass through the chamber to distribute the size thereon, a casing about said brushes opened adjacent the path of the threads and having an opening in a wall thereof through which air may discharge, and heating means positioned directly above the brushes and cooperating therewith to dry the treated threads, said brushes drawing the heat through the threads and out of said opening.
